UNITED STATES PATENT OFFICE.

EDWIN D. STEVENSON, OF WADSWORTH, OHIO.

EQUILIBRATOR FOR FLYING-MACHINES.

1,075,447.

Specification of Letters Patent. Patented Oct. 14, 1913.

Application filed January 15, 1913. Serial No. 742,290.

To all whom it may concern:

Be it known that I, EDWIN D. STEVENSON, a citizen of the United States, residing at Wadsworth, in the county of Medina and State of Ohio, have invented a new and useful Equilibrator for Flying-Machines, of which the following is a specification.

This invention relates to equilibrators for flying machines, its object being to provide means under the control of the motor of the machine for exerting a constant upward pull upon said machine, said pulling means being connected to the machine at a point above the center thereof so that, when the machine tilts out of normal position, the pull exerted by the lifting device will tend to restore the equilibrium of the machine.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings:—Figure 1 is a view showing, diagrammatically, a flying machine in front elevation, said machine being tilted and the equilibrator being positioned to restore the lateral balance of the machine. Fig. 2 is an enlarged side elevation of the equilibrator and showing one way of transmitting motion thereto from the propeller shaft. Fig. 3 is an enlarged section on line A—B Fig. 2. Fig. 4 is a vertical longitudinal section through a modified structure.

Referring to the figures by characters of reference C designates a portion of an aeroplane structure the same being provided with a propeller shaft D adapted to be actuated by a motor E. Extending upwardly from the center of the machine and perpendicular to the sustaining plane or planes is the supporting structure of the equilibrator, this structure being indicated at 1 and being rigidly mounted relative to the frame of the aeroplane.

In the form of device shown in Figs. 1, 2 and 3, a frame 2 is mounted upon the upper end of the structure. This frame 2 supports a gimbal made up of an outer member 3

which can be in the form of a rectangular frame and an inner member 4 which can likewise be in the form of a rectangular frame. The member 3 has trunnions 5 journaled within the frame 2 or within arms 6 extending upwardly from the frame. The member 4 is mounted on a shaft section 7 which extends through the member 3 at right angles to the axis of the trunnions 5. Shaft section 7 has a gear 8 secured thereto which meshes with another gear 9 secured to an upwardly extending shaft 10, this last named shaft being provided, at its upper end, with a helicopter or elevating wheel 11. A rod 12 extends downwardly from the middle portion of the member 4 and is provided at its lower end with a weight 13, this rod and weight thus acting as a pendulum for holding the rod and the shaft 10 normally vertical. Shaft section 10 is connected, by a universal joint 14, to a short shaft section 15 and this section is in turn connected by a universal joint 16 to an angular shaft section 17 which telescopes into another shaft section 18. This last named section is journaled within a bracket 19 extending from the structure 1 and has a pulley 20 or the like for receiving motion, through a belt 21, from a pulley 22 on the shaft D. Obviously a chain and sprocket may be used in lieu of the belt and pulley or any other desired mechanism may be employed for transmitting motion from shaft D to shaft section 18.

By mounting the pendulum in the manner described, it will be seen that the same is free to swing in any direction. Thus it will be seen that should the aeroplane tilt laterally or dip forwardly or backwardly, the pendulum will always remain vertical and the wheel 11 will always be maintained substantially horizontal. As, when the machine tilts out of horizontal position, the gimbal will be shifted away from the vertical center of the machine, as shown in Fig. 1, it will be seen that the upward force exerted by the rapidly rotating wheel 11 will tend automatically to restore the equilibrium of the machine no matter in what direction said machine may tilt.

Under some conditions it might be desirable to provide a helicopter which will only be capable of shifting in a plane extending transversely of the machine. Under these conditions, the same will be mounted as shown in Fig. 4 wherein the supporting structure has been indicated at 23, this

structure corresponding to the structure 1. A frame 24 is mounted within the said structure and is adapted to swing about a shaft 25 which extends longitudinally of 5 the machine and receives motion from the propeller shaft as hereinbefore described. This shaft 25 has a gear 26 meshing with another gear 27 secured to the shaft 28 of the helicopter. A weighted rod 29 similar 10 to the rod 12 is extended downwardly from frame 24. With this construction it will be seen that whenever the machine tilts laterally, the rotating helicopter will exert an upward pull thereon and tend to restore 15 the lateral balance of the machine. It is to be understood that this helicopter wheel is always rotating while the propeller is in operation and, consequently, is always exerting an upward pull upon the machine so 20 that the restoration of the lateral balance is effected automatically whenever the machine tilts out of normal position.

It is to be understood that the helicopter herein described is not in any sense to be 25 considered a means for lifting the flying machine. The machine is intended to soar in the same manner as ordinary heavier than air machines and the helicopter herein described is merely designed as an attachment 30 which can be readily applied to ordinary machines and which merely exerts a lifting force in the manner described for the purpose of restoring the balance of the machine or for maintaining such balance.

25 What is claimed is:—

1. The combination with an aeroplane, of a pendulum controlled helicopter supported above the center of said aeroplane and adapted to swing relative thereto, said 40 helicopter being normally positioned to ro-

tate in a horizontal plane, and means for rotating the helicopter in any position in which it may be supported relative to the aeroplane structure.

2. The combination with an aeroplane, of 45 an equilibrator including a helicopter supported above the center thereof at a point fixed with relation to the frame of the aeroplane, weighted means for holding the helicopter normally in a horizontal plane of 50 movement, and means for rotating the helicopter while the machine is in flight.

3. An equilibrator for aeroplanes including an upwardly extending shaft mounted 55 for movement about a point fixed relative to the frame of the aeroplane and above the center of said frame, weighted means for holding said shaft normally vertical, a lifting wheel revoluble with the shaft, and means for rotating the shaft and wheel 60 while the aeroplane is in flight.

4. The combination with an aeroplane, of an equilibrator including a structure fixedly mounted on the frame of the aeroplane and extending upwardly from the center thereof, a shaft mounted to swing relative to the upper portion of said structure, weighted means for holding the shaft normally vertical, an elevating wheel revoluble with the shaft, and means for rotating the shaft and 70 wheel while the aeroplane is being propelled forward and independent of the angle of the shaft relative to the aeroplane frame.

In testimony that I claim the foregoing 75 as my own, I have hereto affixed my signature in the presence of two witnesses.

EDWIN D. STEVENSON.
